UNITED STATES PATENT OFFICE.

JAMES HASTINGS, OF LIVERPOOL, ENGLAND.

DECORATED METAL PANEL.

Application filed January 2, 1924, Serial No. 683,962, and in England January 3, 1923.

This invention relates to an ornamental covering for walls, ceilings and like surfaces consisting of decorated metal panels as a substitute for wood wainscoting, dadoes, 5 glazed tile-work and similar work. The panelling consists of plates of sheet metal, preferably, tin-plate or black-plate, which are printed, lacquered, enamelled or embossed to imitate wood or glazed tiles or 10 the like, and secured to a framework of wood or other suitable material.

The object of the invention is to provide a composite wall panelling of the kind indicated which can be conveniently assembled 15 on the floor to form a structure complete in itself, which is then raised and secured in a simple manner against the wall surface it is intended to cover. By the method of assembling the panelling away from the surface it is intended to cover, any special preparation of the said surface is avoided, 20 and the panelling can be assembled and fixed in position by an unskilled person.

To these ends, the invention provides wall 25 panelling the components of which are so constructed that when placed in position they interlock and obtain a simplified and self-correcting adjustment of the positions of all the panels contained in the wall section 30 and also ensure a close fit of the panels to each other.

The objects of my invention are achieved 35 by the provision of non-overlapping sheet metal panels and joined intersecting strips of wood to which the panels are secured, the panels having their edges bent backward to 40 form right-angled flanges which are cut away at the corners to form passage-ways to allow the strips of wood to run vertically and horizontally underneath the metal 45 panels and along the flanges of same from one panel to the other through all the panels comprising a wall section. Further, the wooden strips are notched at distances apart 50 corresponding to the lengths of the sides of the metal panels so that when placed in position they interlock and obtain a simplified and self-correcting adjustment of the 55 positions of all the panels in the section and also ensure a close fit of the panels to each other.

The invention will be further described with reference to the accompanying drawings, in which:—

Figure 1 is a rear elevation of sheet metal panelling in accordance with my invention;

Figure 2 is a side elevation of same, and Figure 3 a sectional elevation on the line C—C of Figure 1.

Referring to these drawings, 1 denotes flat 60 metal sheets or panels (of which four are shown, by way of example) the front surface of which is printed, lacquered or embossed to imitate, for example, glazed tiles or woodwork. 2 is a framework of wooden 65 strips to which the panels are attached. To enable the panels to be fitted together in a neat and effective manner, the material along the whole length of the edges of the panels 1 is bent back at right angles to the face 70 of the panel in order to form a flange 8. These flanges are cut away at the corners to allow the strips or battens 2 of the framework to run along the inside of the flanges vertically and horizontally from one panel 75 to the other through all the panels forming a wall section.

The edges of the panels are provided with holes, so that the panels can be attached by nails 9 or screws to the wooden strips 80 forming the framework very quickly and by an inexperienced person. Such nails are, of course, not visible when the panelling is fixed in position.

The framework consists of intersecting 85 vertical and horizontal wooden strips joined together, these strips being notched or rabbeted at distances apart corresponding to the lengths of the sides of the panels, so that a flush surface framework is produced, and a self-correcting adjustment of the framework members and panels is obtained 90 during the assembly of the panelling.

The use of these continuous notched strips, in conjunction with the metal panels the flanges of which are formed with openings 95 to allow the strips of wood to run vertically and horizontally underneath all the panels comprising a wall or ceiling section, enables the assembling of the wooden framework and the panels to be done on a floor or other 100 convenient surface. My system renders the process of assembling perfectly automatic and self-correcting.

The notches or rabbets are made in the wooden strips at distances apart corresponding 105 with the size of the panels, and all that is necessary in assembling the structure is to put the panels, face downwards, on the floor, and place in position on each other, notch in notch, the longitudinal and vertical strips of wood, which when nailed to the 110

flanges against which they lie, build a compact and solid framework. The flanges of the panels are nailed to the strips as the latter are placed in the panels.

5 As I prefer to use these strips of wood and a light tin-plate, the structure is very light, and when complete is then raised and fastened to the wall or ceiling by a few screws or wall-plugs.

10 Any number of panels can be joined together to form all sizes of wall-covering in the manner described, and the uniform depth of the flanges 8 ensures a perfectly flat surface over all the panels forming the wall-covering. By the self-adjusting assembly 15 and the simple method of attaching the panelling to the wall or other surface, no skilled labour is required in assembling and fixing the panelling in position.

20 The metal sheets are first printed, lacquered or embossed in the flat. After these operations, the corners of the sheets are notched or cut away as required, the edges provided with nail-holes, and the metal 25 along the edges of the sheets turned back at a right angle to form the flange.

These metal panels are specially adapted 30 for use in shops and restaurants on account of their hygienic qualities, and in places where fire-danger makes wood wainscoting undesirable.

Two great advantages of my panels over 35 the flat decorated metal sheets now on the market are (1) that they can be attached to or removed from the wall or ceiling without appreciable damage to the said surfaces, and

(2) the framework permits a current of air to pass between the panelling and the wall or other surface. This is a great advantage in new buildings, or where ceilings or walls 40 are inclined to be damp. As these panel sections are assembled on the floor, any costly preliminary preparation of the wall or ceiling for their reception is not necessary. Finally, the panels and the framework strips 45 can be made and sold at a low cost, and can be affixed by any person without requiring any special skill.

I declare that what I claim is:—

A composite covering for walls, ceilings 50 and like surfaces consisting of non-overlapping sheet metal panels, and joined intersecting strips of wood to which the panels are secured, the said panels having their edges bent backward to form right-angled 55 flanges which are cut away at the corners to form passage-ways to allow the strips of wood to run vertically and horizontally underneath the metal panels and along the flanges of same from one panel to the other 60 through all the panels comprising a wall section, and the wood strips being notched at distances apart corresponding with the lengths of the sides of the metal panels, so that when placed in position they interlock 65 and obtain a simplified and self-correcting adjustment of the positions of all the panels contained in the section, and also ensure a close fit of the panels to each other.

In witness whereof I have hereunto signed 70 my name this 18th day of December, 1923.

JAMES HASTINGS.
